UNITED STATES PATENT OFFICE

144,674

DESIGN FOR A STAND FOR A HAND TELEPHONE

Jack Barofsky, Los Angeles, Calif.

Application February 12, 1945, Serial No. 117,905

Term of patent 14 years

(Cl. D26—14)

To all whom it may concern:

Be it known that I, Jack Barofsky, a citizen of the United States, residing at Los Angeles, in the county of Los Angeles and State of California, have invented a new, original, and ornamental Design for a Stand for a Hand Telephone, of which the following is a specification, reference being had to the accompanying drawing, forming part thereof.

Both sides of the design are substantially similar.

The dominant features of my design are shown in solid lines in the drawing.

I claim:

The ornamental design for a stand for a hand telephone, as shown and described.

JACK BAROFSKY.
